BROOM ATTACHMENT

Herbert A. Gardner, United States Army,
San Francisco, Calif.

Application August 16, 1933, Serial No. 685,388

6 Claims. (Cl. 15—247)

(Granted under the act of March 3, 1883, as
amended April 30, 1928; 370 O. G. 757)

The invention described herein, if patented, may be manufactured and used by or for the Government for governmental purposes without payment of any royalty thereon.

5 This invention relates to broom attachments and more particularly to means adapted to secure a mop, duster, polishing cloth or the like over the head of a broom.

An object of this invention is to provide means 10 whereby the desired covering for a broom head such as one of those mentioned may be quickly adjusted in place on the broom or removed therefrom, said last operation of removing the soiled covering after use, being accomplished without 15 handling same.

A further object is to provide a device for securing the covering, that is adjustable and may be applied to brooms of different sizes. Also one of such a character as may remain on the broom 20 after once being adjusted thereto, and is provided with means whereby the mop or other covering may be promptly and securely arranged in place without disturbing the adjustable portion that is mounted on the broom.

25 A further object is to provide a simple device wherein its application to a broom will be readily understood by those who are not ordinarily mechanically inclined, one that is durable due to the fact that the parts are few in number and may be 30 formed of comparatively sturdy metal, and also one of such a construction as may be made very economically and sold profitably at low cost due to the fact that the entire device is made of stamped metal and may be produced practically 35 entirely by machinery, including assembly of parts.

The above and other objects will appear when the invention is more fully understood as pointed out in the following description and claims.

40 A simple form of the device is shown for the purposes of illustration, it being understood that slight changes in form and minor details of construction may be resorted to without departing from the spirit of the invention.

45 Similar numerals indicate corresponding parts in all the figures of the drawings in which:

Fig. 1 is an elevation showing my improved mop securing means applied to the head of a broom.

50 Fig. 2 is a perspective view of the preferred form of attachment.

Fig. 3 is a detail section through one of the clips.

Fig. 4 is a plan view of the blank as cut from stock to produce my improved device.

55 Fig. 5 is a detail plan view of the blank as cut

from stock to produce the pivotal jaw of my improved device.

Fig. 6 is an elevation of a modified form of my device shown applied to the head of a broom.

Fig. 7 is a detail perspective view of the slightly modified form of clamping band of the device, as shown in Fig. 6.

Fig. 8 is an enlarged detail horizontal section through the band and one of the spring clasps shown in Fig. 6.

Fig. 9 is a vertical sectional view taken on line 9—9 of Fig. 8.

Fig. 10 is a plan view of the blank used in forming modified form of device, shown in Figs. 6, 7, 8 and 9.

Fig. 11 is a detail vertical section through a spring clip of a slightly modified form adapted to be permanently mounted on the adjustable band, by rivet.

Reference now being had to the drawings by numerals, 1 indicates the head of a broom, 2 the handle, 3 the usual binding threads of the broom, forming shoulders 4.

This improved device is adapted to be firmly 25 adjusted in place around the broom, preferably on the level of the binding threads 3, and consists of a band of metal or other suitable material 5 that may be stamped from a strip of appropriate material, and is provided with tongue 6 adapted to pass through one of the openings 7 formed in the opposite end of the band and be bent inwardly to firmly secure said band in place after being tightly drawn around the head of the broom. To more firmly retain the band in position and prevent its slipping out of place the 30 material of the band may be roughened by indentations such as shown at 8.

Fig. 4 shows a preferred form of band, that may be cut from a strip of metal or the like, wherein tongue 6 is provided at one end, and openings 7 at the other end of the length of material cut from stock. At suitable intervals along the band, pairs of ears 9 are cut from the stock, and are 40 adapted to be bent perpendicular to the band to bring perforations 10 therein, in line for the 45 reception of pivot pin 11.

On one edge of the band, adjacent to said ears are provided serrated portions as seen at 12, 50 adapted to be bent to form the inner jaws of clips.

Pivots mounted on pins 11 are the outer 55 rocking members 13 of the clips. Said outer members, shown in Fig. 5, may be of stamp metal struck from stock, and provided with perforated ears 14 and serrated lower ends 15, the latter

adapted to be bent at 16 to co-act with serrations 12 to form the jaws of the clips. The clips are normally held closed by coil spring 17 arranged around pins 11 and having their ends in contact 5 with the face of the band and the upper portion of members 13.

By the above means a covering 18 such as a duster, a mop, a polishing cloth, a cloth for applying oil, or a water saturated cloth to prevent 10 the flying of dust while sweeping, regardless of their characteristics, as to weight or thickness may be arranged in such a manner as to entirely cover the broom straws below the binding and be firmly secured in place ready for use in the 15 time required to fold the cloth.

When removing the broom covering and it is desirable to avoid handling same, it is necessary 20 only to lift the broom and press one after another of the clips which hold the covering in place, and it will fall from the broom if desired into a cleansing receptacle (not shown) without requiring the operator to touch same. The coverings are usually applied clean and removed in a soiled condition.

25 In Figs. 6 to 10 inclusive, a slightly modified form of broom attachment is shown, wherein the band 5a is adjustable and is secured in a manner similar to that above described, but the roughened portion is in the form of corrugations.

30 In said modified form, provision is made for removing the clips from the band when desired, said provision being obtained by forming flattened loops 19 in the band and providing spring clips 20 that as shown, may be constructed of stamp 35 metal and provided with a struck up portion 21 in the rear member of the clip, which is so fashioned as to snugly and frictionally fit a flattened loop.

Said structure provides for releasing the mop 40 or other covering of the broom head in the same manner as in the preferred form, or by slipping portions 20 of the clips from the loops 19, the covering may be removed from the broom with the clips attached without unfolding said covering and it will be in condition for quick replacement 45 when desired, by simply bunching the broom straws and inserting their lower ends into the covering which in the latter instance, is in the form of a bag with its clips spaced ready for engagement with the loops in the band.

50 Fig. 11 shows a form of clip adapted to be permanently mounted on the band by rivets 22, and operates to secure the covering in a manner similar to the clips in the preferred embodiment.

55 Having fully described my invention, what I claim and desire to secure by Letters Patent is:

1. A broom attachment adapted to secure a

covering over a broom head comprising a flexible stamped metal band having a roughened surface adapted to prevent vertical displacement of the attachment on the broom head, a plurality of openings in one end of said band and a tongue 5 at the other end of the band adapted to engage one of said openings and firmly and permanently secure the band around a broom head, pairs of perforated ears struck from the band, serrated portions struck from the stock of the band 10 beneath said ears and adapted to form the inner jaws of clips, spring pressed outer jaw members having pairs of perforated ears and serrated lower ends, pivotally mounted on said ears struck from the band and adapted to form the outer jaws 15 of said clips, and secure the cover over the broom head.

2. An attachment for securing a covering on a broom head comprising, an adjustable stamped metal band having a plurality of openings arranged at one end and a pliable tongue at the other for engagement with one of said openings adapted to be firmly and permanently clamped around the broom head and clips arranged at 20 intervals on said band adapted to secure said covering in place.

3. An attachment for securing a covering on a broom head comprising an adjustable stamped metal band having a roughened surface adapted to prevent movement of the band on the broom head and having adjustable means for a permanently mounting the band on a broom head and means for securing said covering to the band.

4. A broom attachment adapted to secure a covering over a broom head comprising an adjustable stamped metal band adapted to be mounted on the broom head having a roughened surface adapted to prevent displacement of the band on the broom head, adjustable means for permanently and securely mounting said band 40 on the broom head, clips consisting of pairs of perforated ears struck up from the band, and stamped metal spring pressed jaws pivotally mounted on said ears, and adapted to secure the covering to the band substantially as specified.

5. An attachment for securing a covering on a broom head comprising an adjustable stamped metal band having means for firmly and permanently securing the band on a broom head, and clips mounted on the band for removably securing the covering to the band.

6. A stamped metal cover retaining device for broom heads, comprising a band firmly and permanently secured around the broom head, and clamping means arranged on the band adapted 55 to secure the covering in place.

HERBERT A. GARDNER.
